UNITED STATES PATENT OFFICE.

HENRY D'OLIER, JR., OF BRIDGEPORT, CONNECTICUT.

LIGHTING FIXTURE.

Application filed December 17, 1924. Serial No. 756,384.

My invention relates to light distributing construction.

One of the objects of my invention is to provide a light distributing construction which will give an advantageous light distribution.

A further object of my invention is to provide a light distributing construction, comprising a translucent diffusing bowl and an opaque reflecting bowl in which diffused light will be distributed above the plane of the lower edge of the reflecting bowl.

A further object of my invention is to provide an improved construction in which free passage is provided for the downwardly directed rays between the diffusing bowl and the reflecting bowl.

Further objects will appear from the description and claim.

20 In the drawings, in which my invention is illustrated:

Figure 1 is a sectional perspective view showing a diffusing bowl with the reflecting bowl surrounding it;

25 Fig. 2 is an axial sectional view through the two bowls; and

Fig. 3 is a table in which the lines corresponding to the various types of rays are designated.

30 The construction shown comprises a diffusing bowl 10 which may be similar to that shown in my prior pending application, Serial Number 657,854, and a metal reflecting bowl 11 surrounding the diffusing bowl 10 and supported thereby. The only direct rays A are those which pass through the opening in the lower part of the diffusing bowl.

The construction is such that neither 40 direct rays A nor "direct reflection" rays B escape from the diffusing bowl at a plane above the plane of the direct rays. By referring to Fig. 1 it will be seen that some of the second reflection rays C do escape above the plane of cone of the direct rays. The diffused rays D which pass through the diffusing bowl are diffused and distributed in every direction and will therefore be reflected in various directions from the inner 45 reflecting surface of the metal reflecting bowl.

It will be noted that the lower edge 12 of the diffusing bowl extends substantially below the lower edge 13 of the outer reflecting bowl so that diffused rays D passing through this lower extending portion will be

diffused and some of these diffused rays D will pass above the plane of the lower edge of the outer reflecting bowl, thus giving a diffused light in a higher plane than could be obtained with the use of the metal reflecting plane alone.

It will be noted that the skirt portions 14 and 15, respectively of the diffusing and reflecting bowls diverge from each other 65 downwardly, permitting a free passage of downwardly directed rays therebetween.

Light distribution curves made using this light distributing construction show an increased light distribution within the 45° 70 zone over that given using the diffusing bowl alone, and show the light distribution above the 90° zone greatly reduced as compared with that of the diffusing bowl alone, but much greater than that obtained using 75 the metal reflecting bowl alone. The combination of the two bowls gives a different and improved result not obtained by the use of either bowl alone. All of the light which reaches the eye from above the "angle of 80 cut-off" either passes through the diffusing glass, or is reflected more than once due to the shape of the glass and to its diffusing characteristic.

If desired, and as shown in Fig. 1, the 85 diffusing bowl 10 may have an upwardly extending conical portion 16 extending through the central opening in the reflector bowl 11 and a substantial distance thereabove so as to allow some diffused light to 90 escape.

The diffusing bowl 10 comprises a downwardly and outwardly extending upper portion 17 and a downwardly and inwardly extending portion 18, and the opaque reflector bowl or shade 11 comprises a downwardly and outwardly extending upper portion 19 overlying the downwardly and outwardly extending portion 17 of the diffusing bowl and a downwardly and outwardly extending 100 lower portion 20 surrounding the downwardly and inwardly extending lower portion 18 of the diffusing bowl.

While I have shown but one form of my invention, it is to be understood that I do 105 not desire to limit myself to this particular construction since many changes and modifications may be made therein without departure from the scope of the following 110 claim.

I claim:

A lighting fixture comprising a diffusing

- bowl of translucent material having a downwardly and outwardly extending upper portion and a downwardly and inwardly extending lower portion, and an opaque reflector shade having a downwardly and outwardly extending upper portion overlying the downwardly and outwardly extending upper portion of the diffusing bowl and extending outwardly there-beyond, and having a downwardly and outwardly extending lower portion surrounding the downwardly

and inwardly extending lower portion of the diffusing bowl, the lower downwardly and inwardly extending portion of the diffusing bowl being open in the bottom and 15 extending below the lower edge of the reflector shade, both the upper and lower portion of said reflector shade being formed as surfaces of revolution about a vertical axis.

In witness whereof, I have hereunto sub- 20
scribed my name.

HENRY D'OLIER, JR.
